CHARLES HARRISON, OF NEW YORK, N. Y.

Letters Patent No. 85,006, dated December 15, 1868.

IMPROVEMENT IN SLOW-CLOSING VALVES FOR WATER-CLOSETS.

The Schedule referred to in these Letters Patent and making part of the same.

To all whom it may concern:

Be it known that I, CHARLES HARRISON, of the city and State of New York, have invented and made a certain new and useful Improvement in Cocks for Water-Closets; and I do hereby declare the following to be a full, clear, and exact description of the said invention, reference being had to the annexed drawing, making part of this specification, wherein—

Figure 1 is a vertical section of the said cock as it is being opened;

Figure 2 is a plan of the piston detached from the barrel; and

Figure 3 is an elevation of the piston and valve separately.

Similar marks of reference denote the same parts.

I make use of a hollow cup-shaped metallic piston, to act upon water in a confined chamber, and control the gradual closing of the valve, said piston being generally of the character shown in Letters Patent granted to me, September 1, 1868.

The nature of my present improvement consists in a grooved water-way, introduced in the edge of the metallic piston, so that a leakage will be produced that allows the water to pass from one side to the other of the piston, as the valve is opened or closed, so that the movement will be sufficiently slow to allow the necessary flow of water, and the valve will not close with a concussion or blow, as is frequently the case from the "ram-action" of the water.

In the drawing—

a is the barrel or cylinder of the valve, to the end, *b*, of which the coupling is attached that unites the water-supply pipe; and

c is the pipe leading to the water-closet.

d is the valve-seat, within the cylinder *a*, and between *b* and *c*.

e is an arm, by means of which the cock may be at-

tached to the hopper of the water-closet, or otherwise sustained.

The valve *f* is upon a stem, *g*, that is prolonged through the packed screw-cap *h*, and provided with a spring, *i*, between the cap *h* and button *k*, that acts to close the valve *f*, after it has been opened by pressure upon the end of the stem *g*, in any usual manner.

The stem *g* is guided in the valve-seat *d* by projecting wings *l*.

The piston *m* is made as a hollow or cup-shaped metallic disk, surrounding the stem *g*, and acting against the water in the chamber *n*, to control the closing of the valve *f*, and prevent sudden concussion by the "ram-action" of the water.

In the edge of the piston *m*, I form a notch, as at *o*, that allows the water to pass into the chamber *n*, as the valve is being opened, as indicated by the arrow, fig. 1. When the pressure upon *g*, to open the valve *f*, is removed, the water gradually passes out of the chamber *n*, through the notch *o*, and allows the valve to close slowly, and without concussion.

This character of valve for water-closets is not liable to become obstructed, and the parts are strong and durable; hence the valve is not likely to get out of repair.

What I claim, and desire to secure by Letters Patent, is—

The metallic piston *m*, formed hollow, and provided with the notch *o*, in combination with the valve *f*, seat *d*, cylinder *a*, and chamber *n*, as and for the purposes specified.

In witness whereof, I have hereunto set my signature, this 3d day of September, A. D. 1868.

CHAS. HARRISON.
